[57] **CLAIM**

The ornamental design for an african american headpiece, as shown.

DESCRIPTION

FIG. 1 is a perspective view of a headpiece showing my new design;

FIG. 2 is a top plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a bottom plan view thereof; and,

FIG. 8 is a perspective environmental view of a headpiece, showing my new design in full lines and the environmental matter in broken lines for illustrative purposes only and forming no part of the claimed design.
